R. A. CHENOWETH

Des. 99,540

SHOE

Filed Dec. 13, 1935

UNITED STATES PATENT OFFICE

99,540

DESIGN FOR A SHOE

Raymond A. Chenoweth, Arlington, Mass.

Application December 13, 1935, Serial No. 60,040

Term of patent 14 years

To all whom it may concern:

Be it known, that I, Raymond A. Chenoweth, a citizen of the United States of America residing at Arlington, in the county of Middlesex and State of Massachusetts, have invented a new, original, and ornamental Design for a Shoe of which the following is a specification, reference being had to the accompanying drawing, forming part thereof.

In the drawing,

Fig. 1 is a side view of a shoe, showing my new design;

Fig. 2 is a similar view of the opposite side of the shoe; and

Fig. 3 is a top view of the shoe shown in Figs. 1 and 2 with the lacing of the shoe unlaced from the loops or eyelets through which it is normally passed, thereby indicating that said lacing is entirely separable from the shoe and may be replaced by another lacing whenever desired.

I claim:

The ornamental design for a shoe, substantially as shown and described.

In testimony whereof I affix my signature.

RAYMOND A. CHENOWETH.
